UNITED STATES PATENT OFFICE.

CHARLES W. DAKE, OF CHICAGO, ILLINOIS, ASSIGNOR TO PYLE-NATIONAL ELECTRIC HEADLIGHT COMPANY, OF CHICAGO, ILLINOIS, A CORPORATION OF NEW JERSEY.

CAR END.

1,239,773.

specification of Letters Patent. Patented Sept. 11, 1917.

Application filed January 27, 1915. Serial No. 4,611.

To all whom it may concern:

Be it known that I, CHARLES W. DAKE, a citizen of the United States, residing at Chicago, in the county of Cook and State 5 of Illinois, have invented a certain new and useful Improvement in Car Ends, of which the following is a specification.

My invention relates to car ends and has for its object to provide a stiffened insulating sheet metal car end adapted to be secured in any desired manner to any kind of car whether of steel or wooden frame.

It is illustrated diagrammatically in the accompanying drawing where I do not show 15 all the details of connection or the details of the car.

Figure 1 is an elevation of a car with my car end attached;

Fig. 2 is a vertical section through the 20 car end proper on the line 2—2 of Fig. 1.

Fig. 3 is an enlarged cross section in the line 3—3 of Fig. 1.

Like parts are indicated by the same letters in all figures.

25 A is the top, B, B the sides, C the bottom sill of a car. D is a plate preferably flat and E is a plate arranged in a parallel plane but separate from the plane of the plate D. The edge of the plate E is prefer- 70 ably bent at F toward the plane of the plate D and provided with an edge G which makes contact with the outer edge of the plate D at J. Between the two plates are a series of spacers which may consist of I beams

35 K, K, channel bars K' K' or of any desired form or shape and bearing upon the opposed surfaces of the two plates. Both are illustrated in the drawings and they may be used simultaneously. These spacers may be ar- 75 ranged in any desired manner vertically or horizontally. The two plates are preferably secured together by the rivets M which co- 80 operate with the thimbles or strips as the case may be. It is possible that such spacers 85

40 might be dispensed with; but the preferred form of my device is that wherein the two plates are spaced and secured together in some such manner as indicated.

45 The sheet metal car end may be secured 90 to the car frame in any desired manner, as for example by the bolts N, N and the two

plates should be secured together either by or in connection with such bolts, or by means of the rivets O, O passing through their respective contiguous rims. In this manner 55 I form a thoroughly stiffened insulated car end which can be attached in any desired manner, either side in, to the frame of the car.

55 In the form illustrated my car end consists of two plates in separated planes secured together, preferably provided with an outer flat rim for engagement with the car frame surfaces and with spacers and securing devices whereby they are rigidly and 60 firmly secured together with a suitable insulation space between them.

65 In this way I get the truss effect to strengthen the car against pressure from either side.

70 The structure so made can, of course, be divided into sections, vertical or horizontal, and the sections be properly attached together. For example, I have shown the car end as composed of two sections with a connecting I beam to which they are riveted. I show the plates as flat, but, of course, their 75 surface configuration could be changed in any desired manner and they may be made of any thickness which experience may justify or the necessity of any particular case require.

75 I have described my invention as a car end. It will be obvious, however, that except for such arrangements as are made for 80 the attachment of the plate or plates to the car end, the sheet metal structure is equally applicable for any other purpose and particularly for the building up of the sides 85 of cars. I wish, therefore, my expression 90 car end, so far as it applies to the sheet metal structure itself, at least to be understood as relating to and covering sheet metal structures of the kind suitable for car ends or for other purposes.

95 I claim:

A car end comprising two flat plates parallel with and separated from one another intermediate spacing members between the plates the edge of one of the plates being bent inwardly about its periphery to engage the other such bending being local-

ized by the periphery so that such bent plate takes the form of a truncated pyramid, and means for fastening the plate edges together and for fastening and locking the plates together upon the spacers and holding the parts all in permanent relation.

5 In testimony whereof, I affix my signature

in the presence of two witnesses this 23rd day of January 1915.

CHARLES W. DAKE.
